UNITED STATES PATENT OFFICE

103,918

DESIGN FOR A TABLE MAT OR SIMILAR ARTICLE

Aaron Traum, New York, N. Y.

Application November 13, 1936, Serial No. 65,889

Term of patent 3½ years

To all whom it may concern:

Be it known that I, Aaron Traum, a citizen of the United States, residing at New York, county of Bronx and State of New York, have invented a new, original, and ornamental Design for a Table Mat or Similar Article, of which the following is a specification, reference being had to the accompanying drawing, forming part thereof, wherein the figure is a plan view of the table mat, or similar article, showing my new design.

I claim:

The ornamental design for a table mat or similar article, substantially as shown.

AARON TRAUM.
